UNITED STATES PATENT OFFICE.

HERMAN E. WHITING, OF PALMYRA, NEW YORK.

HEATER FOR GASEOUS FUEL.

1,102,309.

Specification of Letters Patent.

Patented July 7, 1914.

Application filed July 12, 1912. Serial No. 708,984.

To all whom it may concern.

Be it known that I, HERMAN E. WHITING, of the village of Palmyra, in the county of Monroe and State of New York, have invented a new and useful Improvement in Heaters for Gaseous Fuel, which improvement is fully set forth in the following specification and shown in the accompanying drawings.

10 The present invention relates to heaters for gaseous fuel, that is, to devices for causing a gaseous fuel, in a partially unmixed state after it passes from the carbureter or other source of supply, to be heated in order to vaporize the unmixed particles or 15 globules, and an object of this invention is to provide a simple and inexpensive construction in which the mixture is caused to take such a path that the unmixed particles 20 or globules will be deposited upon a heated surface which will effect their vaporization.

Another object of the invention is to provide a heater having provision for enriching the explosive mixture, the enriching material being fed in such a manner that it 25 commingles with the explosive mixture to give an effective explosion.

To these and other ends the invention consists in certain parts and combinations of 30 parts all of which will be hereinafter described, the novel features being pointed out in the appended claims.

In the drawings: Figure 1 is a side view of the heater connected to a carbureter; 35 Fig. 2 is a vertical section through the fixer; Fig. 3 is a detail view of the two heating devices; and Fig. 4 is a top view of the parts shown in Fig. 3.

According to this invention, there is employed a casing, preferably, embodying three parts, indicated at 1, 2 and 3. The part 1 is contracted at 4 to provide an inlet 5 which is surrounded by a flange 6 adapted to be bolted or otherwise secured to a flange 45 7 on the carbureter 8, the latter being of any suitable construction, but, preferably, of the type which has an upwardly discharging nozzle past which air is drawn. The member 2 is in the form of an open-ended cylinder, while the member 3 is contracted at 9 and is provided with an outlet 10.

Arranged with the chamber, formed by the casing, is a heating chamber 11 which is preferably formed by a ring-shaped casting 50 or wall 12 having outwardly extending flanges 13 and 14 forming respectively the

top and the bottom of the heating chamber and being held within the casing of the heater by shoulders 15 and 16 on casing members 1 and 3 engaging respectively the flanges 14 and 13. It will be seen that the heating chamber 11 has a wall in common with the wall of the heater casing while its inner wall provides a contracted portion within the casing. There may also be provided another heating device arranged between the inlet of the fixer casing and the contracted portion formed by the annular or ring-shaped heating chambers 11. This second heating device is in the form of the chamber 17 which has its side walls 18 converging toward the inlet 5 and its top wall 19 convexed. Extending from the top wall and connecting with the annular heating chamber 11 are passageways 20^a spaced 75 apart to permit the fuel, after passing through the inlet 5 and being deflected toward the side walls of the casing by the cone-shaped walls of the heating chamber 17, to pass above the heating chamber and 80 through the restricted passageway. The convex wall 19 prevents the accumulation of dust or the like.

The heating chambers 11 and 17 may be heated from hot water or other hot fluid 85 passing to the chamber 11 by way of the inlet pipe 20 and from the chamber 17 by way of outlet pipe 21. The filling cup 22 may be connected to the inlet pipe 20 and controlled by a valve 23 for supporting a heating fluid 90 for heating the chambers 11 and 17 when starting the motor. It is also desirable to employ an outlet pipe 24 at the bottom of the chamber 17 for the purpose of providing a circulation from the pipe 20 through the chamber 17. A three-way valve 25 may be employed in the pipe 24 for the purpose of controlling the discharge through such pipe 24. A mixing screen 26 may be arranged within the casing of the fixer above the heating chamber 11, said screen being held by the flange 18 and the shoulder 16 on the member 3.

The invention may also embody a supplemental feed device for a gas to be used either 105 for enriching the fuel or for starting purposes, as, for instance, hydrogen, acetylene gas or oxygen. This is preferably fed to the heater at a point in the center of the same and near the inlet. In this instance, 110 the cone-shaped hollow member 27 is detachably engaged by screw threads 28 or

otherwise with the bottom wall of the heat chamber 17, and the side walls of this cone-shaped member form continuations of the side walls 18 of the heating device. The 5 apex of this member 27 is provided with a nozzle 29 through which the enriching or starting gas or fuel is delivered to the heater, this nozzle discharging in the direction opposite to the direction of the flow of the fuel 10 through the fixer so that the fluid is thereby forced back upon itself and against the cone-shaped device, this impingement together with the simultaneous impingement of the explosive fuel producing a mixture of the 15 two which is completed after the gas passes through the annular heating chamber 11. The feed pipe 30 may connect with the chamber 27 to supply the starting or enriching fluid and may lead to any suitable source 20 of supply and be controlled in any suitable manner.

In starting the motor, heated water or other fluid may be caused to travel from the cup 22 to the discharging valve 25 through 25 the chambers 11 and 17, thus heating the walls of such chambers. An explosive mixture, such, for instance, as gasoline or acetylene gas may be directed to the heater casing by way of feed pipe 30 and nozzle 29, 30 passing from the nozzle in contact with the heated walls to the cylinder. After the motor is started, the chambers 11 and 17 are, by pipes 20 and 21, placed in connection with the water jackets of the motor and, in this 35 way, the walls of these chambers are kept warm. The explosive mixture, passing through the inlet 5, first hits the cone-shaped device centrally arranged within the fixer casing. The walls of this device, being 40 heated, fix the mixture and, at the same time, deflect the same against the bottom wall of the annular heating chamber 11, after which the mixture passes through the reduced opening in the annular chamber, thus becoming 45 effectively fixed. The mixture may be enriched or modified by the introduction of any suitable fluid through the nozzle 29 and this enriching fluid is effectively mixed by reason of the circuitous passage through 50 which the mixture is caused to travel.

What I claim as my invention and desire to secure by Letters Patent is:—

1. A heater for gaseous fuel comprising a casing, an annular heating device within 55 the casing having a central passageway for the mixture, and a cone-shaped device located centrally within the casing with its apex arranged to be engaged first by the incoming mixture, the walls of said cone-shaped device being smooth and unobstructed to permit the mixture to spread over the flaring side walls which direct the mixture upon the annular heating device.

2. A heater for gaseous fuel comprising 60 a casing, an annular chamber for a heating

fluid, arranged within said casing and having a central passageway for the fuel, and a cone-shaped heating chamber arranged centrally with reference to the annular heating chamber with its apex located to be engaged 70 first by the incoming fuel which is then spread over the flaring walls of the cone-shaped chamber and directed by the latter against the walls of the annular heating chamber.

3. A heater for gaseous fuel comprising a casing, an annular chamber for a heating fluid, arranged within said casing and having a central passageway for the fuel, and a cone-shaped heating chamber arranged centrally with reference to the annular heating chamber with its apex located to be engaged 80 first by the incoming fuel which is then spread over the flaring walls of the cone-shaped chamber and directed by the latter against the walls of the annular heating chamber, the wall of said cone-shaped chamber in proximity to the heating device being convex, so that fine particles will not collect upon the heating device, and a dead 85 space will not be provided above the said heating device.

4. A heater for gaseous fuel comprising a casing having a restricted inlet, a cone-shaped spreading device having its apex directed toward the inlet and arranged centrally with reference to said inlet, the base of said cone-shaped spreading device being greater in diameter than the inlet, and heating means on which the fuel is directed by 90 the cone-shaped spreading device.

5. In a heater for gaseous fuel, the combination with a casing embodying three parts, one of which has an inlet, another of which has an outlet, and the other of which 105 is an open-ended member, of a tubular member having outwardly-extending flanges at opposite ends co-operating with the open-ended member to provide an annular heating device within the casing.

6. In a heater for gaseous fuel, the combination with a casing having a reduced inlet and a reduced discharge; of an annular heating chamber having a wall in common with the casing and forming a reduced 110 passageway in the casing, and a spreading device arranged centrally within the casing between the inlet and the reduced passage to cause the fuel passing into the casing to impinge such spreading device and to be directed against the walls of the annular chamber, a passageway being provided about the spreading device to permit the fuel to pass through the annular heating device.

7. In a device of the class described, the 115 combination with a casing having a fuel inlet and a fuel outlet, of a heating device arranged within the casing, a spreading device arranged within the casing in the path of the fuel passing through the fuel inlet to 120

direct the fuel on the heating device, and a nozzle arranged to discharge into the casing between the fuel inlet and the spreading device so as to cause a fluid from the nozzle 5 to pass over the spreading device.

8. In a device of the class described, the combination with a casing having an inlet, of a cone-shaped heating device arranged within the casing and having its apex located to be engaged first by the incoming 10 fuel which is then spread over the walls of the cone-shaped heating device, and a nozzle arranged at the apex of the cone to discharge toward the inlet of the casing so that the fluid issuing from the nozzle is caused to return upon itself and spread over 15 the walls of the cone-shaped heating device.

9. In a device of the class described, the

combination with a casing having an inlet and an outlet, and an annular heating device arranged therein and having a central passage for the mixture, of a cone-shaped device arranged centrally with reference to the annular heating device and having its apex directed toward the incoming mixture, 20 and a nozzle arranged at the apex of the cone-shaped device and directing a fluid toward the incoming mixture so that such fluid is returned upon itself and spread over the walls of the cone-shaped device to be 25 directed by the latter onto the annular heating device.
